UNITED STATES PATENT OFFICE

2,031,476

TAGGING MACHINE

Ralph W. French, Junction City, Kans.

Application January 8, 1934, Serial No. 705,763

8 Claims. (Cl. 93—88)

This invention relates to tagging machines and more particularly to a device for use in laundry and cleaning establishments in applying stapled tags to garments for identification purposes and has for its principal objects to provide a simple and inexpensive machine for automatically clinching stapled tags, to provide means for facilitating insertion of tags into the machine, to provide an improved die construction wherein the staples are accurately spaced to retain the tag in close relation to the garment, and to provide a yieldable garment support in connection with one of the dies to prevent stretching that might tend to tear the garment.

In accomplishing these and other objects of the invention, I have provided improved details of structure, the preferred form of which is illustrated in the accompanying drawing, wherein:

Fig. 1 is a perspective view of a stapled tag applying machine constructed in accordance with my invention.

Fig. 2 is a side elevational view of the device.

Fig. 3 is a vertical sectional view through the die members for clinching the staples of the tag to a garment.

Fig. 4 is an enlarged detail sectional view through the dies illustrating the position of the dies at the time the staples begin to penetrate a garment carried by the garment support.

Fig. 5 is a similar view showing the relative position of the dies and work support just prior to final clinching of the staples.

Fig. 6 is a detail perspective view of one of the stapled tags, as used in the machine.

Fig. 7 is a perspective view of the tag guide whereby the tags are guided for movement into the upper die.

Referring more in detail to the drawing:

1 designates a stapled tag applying machine including a base plate 2 having openings 3 therein through which fastening devices, such as screws 4 are extended to secure the machine to a table or other support 5.

Extending upwardly from one side of the base plate and spaced from its side edge is a frame member 6 having a forwardly extending portion 7 spaced from the upper face of the base plate to accommodate, therebetween, upper and lower die members 8 and 9, respectively.

The upper die member 8 constitutes a substantially T-shaped hammer head portion 10 having an upwardly extending shank 11 that is reciprocably mounted in a guide opening 12 in the extension 7 of the frame. The shank 11 and the guide opening therefor are preferably rec-

tangular in cross section, so as to prevent rotation of the upper die relatively to the lower die 9 when it is reciprocated to and from clinching position as hereinafter described.

The upper end of the shank 11 is provided with a slotted portion 13 to form spaced ears 14 and 15 between which is mounted a rock lever 16, the lever being pivotally connected with the ears by a screw 17 extending through openings in the ears and a slot 18 formed in the end of the lever to allow for arcuate movement thereof when the lever is actuated to reciprocate the upper die member.

The rear end of the lever is pivotally connected by a screw 19 to spaced ears 20 and 21 carried on the rear upper corner of the frame member.

The rock lever 16 is operated through a connecting link 22 which is connected to a foot pedal 23 pivotally mounted on the floor by a bracket 24. The bracket 24 includes a plate portion 25 that is attached to the floor by fastening devices 26 and has upwardly extending ears 27 and 28 for pivotally mounting the lever portion 29 of the foot pedal.

The link 22 comprises a rod having yoke shaped heads 30 and 31 that are pivotally connected to the rock lever at a point between the fulcrum thereof and the shank of the die and to the lever portion 29 of the foot pedal respectively, the connections being provided by pins 32.

The upper die is normally retained in its uppermost position by a coil spring 34 having one end secured to an eye 35 carried by the base plate and its opposite end secured to an eye 36 of an adjusting screw 37 that is threaded into an opening in the rear end of the rock lever.

The adjusting screw may be locked in adjusted position by a nut 38 threaded on the projecting end of the screw and engaging the upper face of the lever, as shown in Figs. 1 and 2.

Extending from the frame member 6 and preferably formed integrally with the base plate is a lateral frame extension 39 having a vertical front face 40 extending in the plane of the front face 41 of the frame 6 while the rear face 42 thereof extends diagonally toward the rear edge of the frame 6 to provide space above the base plate for a tag receptacle 43.

The receptacle 43 preferably includes a dish-shaped member having a laterally extending peripheral flange 44 adapted to engage a ring 45 carried on a bracket arm 46 that is pivotally mounted in an opening 47 in the upper face of the frame extension.

The die members 8 and 9 are shaped to accommodate a standard stapled tag comprising a short strip of fabric or like tape 48 having staples 49 and 50 with their prongs 51 and 52 extending through the strip adjacent the ends thereof as shown in Fig. 6. The bar portions 53 of the staples are of such length to allow the prongs to be spaced inwardly from the side edges 54 and 55 of the strip.

10 The upper die member is provided on its under face with a channel shaped groove 56 having substantially the same width as the strip portion 48 of the tags and having inwardly extending ribs or claws 57 and 58 projecting inwardly 15 and extending longitudinally of the vertical sides 59 and 60 of the groove to form supports 61 and 62 for the side edges of the cloth tags whereby the bar portions of the staples are retained on the bottom or hammer face portion 63 of the die member.

20 In order to facilitate placement of the stapled tags so that the side edges 54 and 55 thereof may be moved in guided relation into the die member for support by the claws 57 and 58, I 25 provide a tag guide member 64 comprising a flat block 65 having spaced longitudinally extending slots 66 and 67 opening from the end thereof adjacent the upper die.

20 The slots 66 and 67 divide the block into spaced 30 fingers 68, 69 and 70 which engage the under face of the tags to support them in alignment with the upper face of the claws 57 and 58 with the prongs 51 and 52 depending within the slots.

35 In order to support the member 64 so that the end thereof can be adjusted relatively to the groove of the die, it is provided with a laterally extending pin 71 which is received in an opening 72 formed in the front face of the frame extension 39. The supporting member 64 may thus 40 be moved laterally of the head to position it so that the sides of the tag are positioned to enter the channel-shaped groove of the die, and pivoted so as to adjust the free end of the fingers relatively to the height of the die. After adjustment, the supporting member may be retained in selected position by a thumb screw 73 threaded into an opening 74 in the frame extension and having an end engaging against the pin 71.

50 In order to gage the position of the tag in the die, the end of the groove 56 opposite the supporting member 64 is closed by a stop bar 75 while its opposite end is provided with a finger recess 76 to accommodate the finger of the operator in shoving the tag from the guide support into the die.

55 The lower die includes a block or anvil 77 that is supported above the base plate on legs 78 and 79 directly in alignment with the upper die and in position so that the claws thereof will move over the parallel side faces 80 and 81 of the anvil.

60 The anvil 77 is of sufficient length to conform to the spacing of the staples and its upper face 65 is provided with spaced parallel concave grooves to form guiding surfaces whereby the prongs of the staples are moved into clinching position as later described.

65 In order to support the work above the level 70 of the anvil to permit substantially complete penetration of the prongs before clinching begins, the lower die also includes a work supporting member 82 comprising a rectangular shaped frame having a recess 83 formed therein to accommodate the anvil portion of the die, as clear-

ly shown in Figs. 3, 4 and 5, so that the sides 84 thereof extend above the surface of the die and form supports for the garment.

75 The bottom plate portion 85 of the frame is provided with spaced openings 86 and 87 for accommodating the legs supporting the anvil.

80 During clinching of the prongs, the garment support is moved downwardly over the anvil legs by contact of the upper die with the garment, the garment support being normally supported by 10 coiled springs 88 and 89 which are sleeved over the anvil legs.

85 The legs 78 and 79 of the anvil are secured to the base plate by screws 90 extending through openings 91 in the base plate and having threaded shanks engaging in threaded sockets 92 in the legs.

90 In operating a machine constructed and assembled as described, the receptacle 43 is filled with stapled tags, such as shown in Fig. 6. When 20 a tag is to be applied to a garment, the tag is removed from the receptacle and placed on the supporting member 64 with the prongs 51 and 52 thereof extending in the slots 66 and 67. The portion of the garment to be tagged is then 25 stretched across the garment support, after which the tag is slid into position in the upper die so that the side edges 54 and 55 thereof are supported by the claws 57 and 58 with the prongs of the tag extending in the direction of the garment.

95 The foot pedal 23 is then depressed to rock the lever 16 to move the upper die or anvil head toward the garment. As the head approaches the garment, the prongs 51 and 52 of the tag will 35 engage and be projected through the garment by the time the claw portions of the upper die engage the upper face of the garment.

100 The claw portions of the die are then in substantial contact with the upper face of the garment.

105 Continued downward movement of the upper die effects downward movement of the work support against tension of its supporting springs 88 and 89. Simultaneously with downward movement of the work support, the points of the prongs engage the concave grooves of the anvil and are guided into clinching position, as shown in Fig. 5. In final clinched position, the upper portion of the anvil enters the tag retaining channel of 50 the upper die only the depth of the claws so that there is little or no stretching of the garment that might tend to tear the fabric.

110 Upon release of the pedal, the spring 34 which has been tensioned on downward movement of 55 the die will return the upper die to retracted position to cause withdrawal of the tag therefrom for the reason that the garment is still retained in taut condition over the garment support by the operator.

115 As soon as pressure is released on the garment, the springs 88 and 89 will return the garment support to normal position, after which the garment is removed, completing the operation.

120 From the foregoing, it is apparent that I have 65 provided a simple, inexpensive machine for automatically clinching stapled tags to garments in such a manner that there is little or no stretching action of the garments, while the tags are being applied, which might tend to tear the 70 fabric.

125 What I claim and desire to secure by Letters Patent is:

130 1. In a machine of the character described, a support, an anvil carried by the support, a ham- 75

mer member mounted on the support for movement to and from the anvil, means for actuating the hammer member, means on the hammer member for supporting a stapled tag with prongs projecting toward the anvil, a guide member, means for pivotally mounting the guide member on the support for guiding the tag into said tag supporting means on the hammer member, a work support, and means carrying the work support for movement relatively to the tag supporting means on the hammer member above the anvil to effect penetration of the prongs through the work and movable over the anvil under force of the hammer member whereby the prongs are clinched

15 on the anvil.

2. In a machine of the character described, a support, an anvil carried by the support, a hammer member mounted on the support for movement to and from the anvil, means on the hammer member for supporting a stapled tag with prongs directed toward the anvil, a guide member carried by the support for guiding the tag into said tag supporting means on the hammer member, means pivotally adjusting the guide member relatively to the tag supporting means, and a work support yieldingly carried above the anvil to effect penetration of the prongs through the work and movable over the anvil under force of the hammer member whereby the prongs are clinched on the anvil.

3. In combination with hammer and anvil members and means for supporting a stapled tag on one of the members, a guide member having finger portions forming a support for the tag and slots to receive prongs on the tag, and means for supporting pivotally the guide member relatively to said tag supporting means whereby a stapled tag is moved in guided relation into said supporting means.

4. In a machine of the character described, a support, an anvil carried by the support, a hammer member provided with a flat face and having a shank portion, means slidably mounting the shank portion of the hammer member on the support for vertical movement to and from the anvil, a rock lever pivotally mounted on the support and connected with said shank portion, an actuating lever connected with the rock lever, means on the hammer member for supporting a stapled tag in contact with said face with prongs projecting toward the anvil, a work support yieldingly carried above the anvil to effect penetration of the prongs through the work and movable over the anvil under force of the hammer member whereby the prongs are clinched on the anvil, and a guide member carried by the first named support for guiding the tag into said tag supporting means on the hammer member.

5. In a machine of the character described, a support, a rectangular shaped anvil carried by the support, a hammer member conforming in shape to the anvil and provided with a channel shaped seat for accommodating a tag having staples including cross bar portions adapted to engage said seat and prongs projecting through the tag in the direction of the anvil, a garment supporting frame slidable over the anvil and having side and end portions of the frame spaced from the prongs, means mounting the hammer

for vertical movement on the support to carry the prongs vertically through the garment while the garment is held on the support, and means yieldingly retaining the garment support with the garment in spaced relation with the anvil while the prongs are being passed through the garment and yieldable upon pressure of the hammer against the garment to move the garment over the anvil for effecting clinching of the prongs against the anvil.

6. In a machine of the character described, a support, an anvil carried by the support, a hammer member provided with a channel shaped seat open at one end for accommodating a tag having prongs extending through the tag in the direction of the anvil, a tag guide carried by the support and having spaced fingers aligning with the open end of the channel to provide guide slots to receive the prongs for guiding the tag in movement into said channel shaped seat, a garment supporting frame slidable over the anvil and spaced from the prongs of the tag, means mounting the hammer for vertical movement on the support for carrying the prongs vertically through the garment while the garment is held on the support, and means yieldingly retaining the garment support with the garment in spaced relation with the anvil while the prongs are passing through the garment and yieldable upon pressure of the hammer against the garment support to move the garment support over the anvil for effecting clinching of the prongs against the anvil.

7. In a machine of the character described, a support, an anvil carried by the support, a hammer member mounted on the support for movement to and from the anvil and having a flat face portion, means for actuating the hammer member, means on the hammer member for supporting a stapled tag in contact with said flat face portion and with prongs directed toward the anvil, a guide member carried by the support for guiding the tag into said hammer member for support by said supporting means, a work support having a recess for the anvil, means for adjustably positioning the guide member to align said guide member with the tag supporting means, and means yieldingly mounting the work support for sliding movement over the anvil to effect penetration of the prongs through the work and movable over the anvil under force of the hammer member, whereby the prongs are clinched on the anvil.

8. In a machine of the character described, a support, an anvil carried by the support, a hammer member mounted on the support and provided with a face for backing against the cross bars of staples in a stapled tag for movement to and from the anvil and having claws for supporting the stapled tag with said cross bars in contact with said backing face and with prongs of the staples projecting toward the anvil, a work support yieldingly carried above the anvil to effect penetration of prongs through the work and movable over the anvil under force of the hammer member to effect clinching of the prongs against the anvil.

RALPH W. FRENCH.
